WIREWAY WITH ADJUSTABLE WIDTH
SIDEWALLS

Irving F. Weiss, Cleveland, Ohio, assignor to E. C. P. Manufacturing Co., Cleveland, Ohio, a corporation of Ohio

Filed Sept. 12, 1960, Ser. No. 55,342
12 Claims. (Cl. 174—101)

This invention relates to wireway devices for housing and protecting multiple wire leads in complex electrical devices, such as control panel construction.

Electric control panels house many control mechanisms including a multitude of electrical wires leading to and from the control mechanisms. It is often desirable or even necessary to establish a definite physical pattern of such wires and to run the wires in an orderly accessible fashion between the control mechanisms within the control panel and points outside the control panel. In order to obtain an orderly and controlled pattern of wiring, so-called wireways are used.

Basically, a wireway includes a casing defining an internal wire passageway into which wires may be introduced through openings, and preferably, a cover to close the casing. The wires are strung along the wire passageway to a predetermined outlet or to another passageway and thereafter to an outlet. In a construction of wireways it is desirable to have a cover that is removable to permit access to the internal passageway. Access is necessary to originally install the wires and equally necessary to permit repair of existing circuits and installation of additional mechanisms and associated circuits. Desirable characteristics of the removable cover include facile attachment and removing of the cover from the casing, and suitable fastening means which will retain the cover in place during use irrespective of warpage or bending of the casing. There are wireways available which are extruded composition material but having a number of shortcomings with respect to original installation, defects in closure, effective use after installation, and inflexibility of design requiring large inventories.

Therefore, one of the principal objects of this invention is to provide a cover attachment for a wireway which will enable the cover to be easily installed and removed.

Another object of this invention is to provide a guide and beading interlock enabling a wide tolerance of structural dimensions of the interlock with no loss in holding properties.

A further object of this invention is to provide a wireway construction enabling the substitution of parts for channel-size adaptation, without necessitating an entire-size stockpile, and which construction is versatile for vernier adjustment of a channel with a given set of channel parts.

Other objects and a fuller understanding of the invention may be had by referring to the following description and claims taken in conjunction with the accompanying drawings in which:

FIGURE 1 is a front elevational view of a control panel with parts broken away to show several wireways in use;

FIGURE 2 is an internal section view taken on line 2—2 in FIGURE 1 and shows wires leading into a central channel;

FIGURE 3 is an exploded perspective view of the parts of the wireway; and,

FIGURE 4 is a detail view of the beading and guide construction of the side rails and top cover of the wireway.

Referring now to the drawings, and particularly to FIGURES 1 and 2, a control panel employing several wireways 10 is shown. The control panel has electric

2

devices 11 mounted thereon, and each device 11 has a plurality of wires 12 leading therefrom. The wires 12 lead through wire openings 28 into a wire passage 14 formed by the wireway 10. The wires form a bundle as indicated at 13.

Referring now to FIGURES 3 and 4, the construction of this new and improved wireway is shown. An elongated base plate 20 is provided having bolt accepting apertures 21 formed therein. The apertures 21 take the form of elongated slots. The base plate 20 also has a pair of channels 22 which extend substantially the entire length of the base plate 20. Each channel 22 includes and is defined by a pair of opposed L-shaped members 23 which are parallel and a back portion 42 between the parallel L-shaped members 23.

A pair of side rails 25 are provided. Each side rail 25 has a T-shaped base 26 and a wall portion arranged at right angles to the arms of the T-shaped base 26. Each T-shaped base 26 is shaped and positioned to slide into one of the channels 22. The bases 26 as they project from the walls of the side rails 25 are thus slidably received within the grooves defined by the channels 22 and are releasably retained by the channels 22. The bases 26 are thus flange projections which are received within projection receiving grooves formed by the channels 22. Each base 26 also includes a plurality of bolt receiving apertures 30 which, in the preferred and disclosed embodiment, take the form of elongated slots. The slots 30 are positioned to register with the bolt receiving apertures 21 of the base when the base 26 is positioned in a channel 22. The T-shaped bases 26 are not bisected by the remainder of the side rail, but rather are offset. With such a structure, the width of the wide passage can be varied depending upon which way the side rails are slid into the channel.

A plurality of wire openings 28 are formed in the wall portion of each side rail. These openings are in the form of rectangular cutouts which extend laterally relative to the longitudinal axis of each side rail. It is through these openings 28 that the wires 12 lead into the wire channel 14.

An enlarged beading 29 is formed at the top of each side rail 25 and extends the entire longitudinal length of each side rail. This enlarged beading 29 in cross-section is generally tear-drop shaped and forms one element of the novel and improved interlocking mechanisms.

A cover 31 is provided having a pair of elongated flange members 32. Each flange member is defined by a pair of distensible resilient side walls 33, 33a. As can best be seen in FIGURE 4, one of the side walls, and preferably inside side wall 33a, is longer than the other side wall. The reason for such construction will be described presently. The side walls 33, 33a each have inner surfaces which define a tapered slot 34, a neck 35, and a socket 36. This forms a guide and interlock structure for the beading 29. The socket 36 is in the form of a segment of a circle. As can best be seen in FIGURE 4, the distance across the beading 29 is less than the diameter of the circle described by the socket 36 and greater than the distance across the neck 35 when the side walls 33, 33a are not distended.

The cover 31 shown in FIGURE 3 is sized to accommodate the side rails when the side rails form a maximum size wireway passage as is shown. If one or both of the side rails 25 are reversed to provide a narrower wireway passage, then a different smaller cover 31 is more conveniently used.

In the preferred and disclosed embodiment a resilient plastic is used to form the entire wireway. Plastic has been chosen because of its ease of fabrication, resiliency, non-inflammable, and non-conductive properties.

3
Method of Assembly

The following is a method of assembling the wireway for use in a control panel:

First, the two side rails are engaged with the base plate 20 by inserting the bases 26 of the side rails into opposite channels 22 and aligning the apertures 21 and 30. The base plate and side rails, as thus assembled, are bolted or otherwise secured onto a control panel at a preselected location. The wires 12 are then run from the control mechanisms 11 through the side rail openings 28 and into the internal wire passage 14.

The wires are then led along the wire passage 14 to the end of the passage which terminates either at the outside of the board or at another wireway. When the wiring has been completed, the cover may be positioned by either of two methods.

(1) The beading 29 of one side rail is placed in the tapered slot 34 of one of the flange members 32 and pressure applied against the top to urge it toward the base plate 20. Under such pressure, the side walls 33, 33a of the flange member will yield and distend to allow the beading 29 of each side rail to pass through the neck 35 and engage in the socket 36. The flexibility of the side walls 33, 33a are greatly improved and enhanced by the provision of a pair of longitudinally extending flutes 40, 40a associated with each flange member 32. Each flute 40a is formed at the juncture of side wall 33a and the base plate 20, and each other flute 40 is formed in the base plate in alignment with the socket 36. The flutes 40, 40a in addition to permitting greater distensibility of the walls 33, 33a, also reduce the force needed to urge the beading 29 into the socket 36.

After beading 29 has passed through the neck 35, the opposite walls 33, 33a will return to their former position from their distended position, and the connection will have been securely made.

After one side has been thus secured, the opposite side is brought into alignment and pressure exerted to secure that side of the cover. The advantage of such beading and guide type of interconnection is that if the channel is packed excessively full, the side rails can be bulged to some extent and the socket nevertheless brought into alignment as described and a tight juncture made. Furthermore, resilient plastic is difficult to properly align and, thus, the side rails may be progressively aligned as pressure is applied; and hence, the union of the parts can be carried on progressively from one end of the channel to the other. Furthermore, if the channel is insufficiently filled, and the side rails tend to fall together, they are nevertheless capable of being securely locked by such beading and guide construction in counter-distinction to former types of overlapping hook-type closure devices which depend upon full lateral extension of the side rails to hold the cover on the casing.

If the wire passage is excessively full and the side rails are bulged to a substantial extent, force must be exerted against the side rails to bring them into alignment with the tapered entrance slot 34. To assist and aid in such an alignment, the inner side wall 33a of each flange member extends beyond the other side wall 33. Hence, the cover 31 can be engaged with one side rail and thereafter the other side rail is bent inwardly until it strikes the elongated side wall 33a, thus positioning the beading. Then, the beading is pushed into engagement in the socket as described.

(2) The cover may also be placed on the side rails 25 by aligning the sockets 36 of the flanges with the beading 29, and sliding the cover 31 longitudinally with respect to the side rails 25. This same sliding movement can be used to remove the cover 31.

In large installations for reasons of economy or saving of space, it may be undesirable to have a base plate. The devices of this invention is extremely well suited for such installation. If no base plate is required, the bases 26 of the side rails 25 are bolted or secured directly to the con-

4
trol panel through the slots 30 at a proper spacing. The remainder of the assembly operation is identical to that as described above.

This type of installation particularly points up the advantage of this device in correcting for misalignment. Because of the nature of the device, the side rails frequently are secured to the panel such that there is not an exact alignment between the flanges 35 and the beading 29. However, since plastic is resilient and flexible, side rails can easily be flexed so that the beading 29 will fit into the socket 36 to provide a secure connection. Similarly, misalignment will be corrected if it is due to warpage, or due to pressure on the side rails.

In summary, the invention is believed to comprise a new and novel wireway having a pair of side rails with enlarged beading members at the top of the side rails, and a cover having a guide and socket construction to interlock with the beadings on the side rails to provide facile assembly and disassembly and maintain a well secured cover.

Although the invention has been described in its preferred form with a certain degree of particularity, it is understood that the present disclosure of the preferred form has been made only by way of example and that numerous changes in the details of construction and the combination and arrangement of parts may be resorted to without departing from the spirit and the scope of the invention as hereinafter claimed.

What is claimed is:

30 1. A wireway, comprising, an elongated base plate, a pair of spaced elongated side rails carried by said base plate, means to mount said base plate and said side rails on a separate structure, said side rails having wire admitting openings in a wall portion thereof, the wall portion having a uniform thickness throughout substantially its entire extent, each of said side rails including an elongated beading spaced from said base plate, each beading extending along substantially the entire length of its side rail, said beading having a generally circular outer surface and tapered side surfaces so as to have generally a tear-drop shaped cross-section, said circular outer surface defining a longitudinal edge of the side rail and said tapered portions being adjacent to the wall portion of the side rails, the wall portion adjacent the beading having a thickness less than the largest dimension of the beading, said wire admitting openings extending to adjacent said beading, an elongated cover, said cover having a pair of spaced flange members extending substantially the entire length of said cover, each of said flange members including a pair of distensible side walls, the side walls of each flange member defining a tapered entrance slot, a neck portion, and a socket, said neck portion having a width that is less than the largest cross-sectional lateral dimension of said beading of said side rail, said socket having generally a shape in cross-section of a segment of a circle, the diameter of said circle being greater than the largest lateral dimension of said beading, each of said flange members receiving the beading of one of said side rails, and said neck portion gripping the wall portion adjacent the beading.

60 2. In the device of claim 1, said base plate including a pair of longitudinally extending channels, and each of said side rails including a T-shaped base shaped and removably inserted in said channels.

65 3. A wireway, comprising, an elongated base plate, a pair of spaced elongated side rails removably carried by said base plate, mounting means to mount the base plate and side rails on a separate structure, said side rails having wire admitting openings therein, each of said side rails including an elongated beading spaced from said base plate, each of said beadings extending along substantially the entire length of its side rail, said beading having generally a tear-drop shaped cross-section, an elongated cover, said cover having a pair of spaced flange members extending substantially the entire length of said

cover, each of said flange members including a pair of distensible side walls, the side walls of each flange member extending different distances from said cover, a pair of flutes associated with each of said flange members, each flute being formed in said cover and extending substantially the entire length of the cover, the side walls of each flange member defining a sloping entrance slot, a neck portion, and a socket, said neck portion having a width that is less than the largest cross-sectional lateral dimension of said beading, said socket having generally the shape in cross-section of a segment of a circle, the diameter of said circle being greater than the largest lateral dimension of said beading, each of said flange members being positioned to receive the beading of one of said side walls.

4. A wireway comprising, a pair of spaced elongated side rails, each of said side rails including mounting means, said side rails having wire admitting openings therein, each of said side rails including an elongated beading, each beading extending along substantially the entire length of its side rail, an elongated cover; said cover having a pair of spaced flange members extending substantially the entire length of said cover, each of said flange members including a pair of distensible side walls, the side walls of each flange member defining an entrance portion and a socket, each of said flange members receiving the beading of one of said side rails and the inner side wall of each flange member being longer than its corresponding outer side wall.

5. A wireway for retaining electrical wires in an orderly and accessible formation comprising, a pair of spaced elongated rail-like side walls, each of said rail-like side walls including a base and an elongated beading, said base being an off-center T in cross section with the one arm of the T longer than the other, the arms of the T comprising a mounting flange adapted to be mounted on a base structure, said pair of spaced elongated rail-like side walls being removably mountable on the same base structure in any one of several different relative positions, said several different relative positions providing a channel-like wireway of different widths, said elongated beading extending along substantially the entire length of its respective rail-like side wall, an elongated cover, said cover having a pair of spaced flange members extending substantially the entire length of said cover, each of said flange members including a pair of distensible side walls, said distensible side walls being adapted to receive and retain the elongated beading of said rail-like side wall, and said cover being mounted on said pair of spaced rail-like side walls by placing the cover over the channel-like passageway formed by the rail-like side walls and snapping each flange member over the beading of its respective rail-like side wall.

6. A wireway for retaining electrical wires in an orderly and accessible arrangement comprising:

- (a) an elongated base plate, said base plate including a pair of channel retaining members longitudinally disposed one adjacent each longitudinal edge of said elongated base plate;
- (b) means to mount said base plate on a separate structure;
- (c) a pair of elongated side walls, each of said pair of side walls including a base;
- (d) said base having a flange portion adapted to be slidably inserted into one of said channel-shaped retaining members, said flange portion of each of said pair of elongated side walls being removably inserted into their respective channel-shaped retaining members to form a channel-like passageway for supporting electrical wires;
- (e) each of said pair of elongated side walls including a beaded portion extending longitudinally along the top thereof;
- (f) an elongated cover, said cover having a pair of spaced flange members extending substantially the entire length of said cover;

5
10

20
25

30
35

40

60
65

(g) each of said flange members including a pair of distensible side walls, said distensible side walls being adapted to receive and retain the elongated beading of said side walls, said cover being mounted on said pair of side walls by placing the cover over the channel-like passageway formed by the side walls and snapping each flange member over the beading of its respective side walls; and

(h) each of said pair of side walls having openings to permit electrical wires to leave and to enter the channel-like passageway.

7. In the device of claim 1 said side rails having elongated flanges and said base plate having portions defining elongated flange receiving grooves whereby said side rails are removably securable on said base plate by sliding the flanges into the flange receiving grooves.

8. Wireway sidewall material comprising:

- (a) an extruded elongated body of synthetic plastic material, the elongated body having an elongated base and an elongated wall upstanding from the base;
- (b) the wall having a tear-drop shaped beading along its longitudinal edge opposite said base, the wall being of substantially uniform thickness throughout between said base and said beading;
- (c) said beading having a generally rounded portion defining the longitudinal edge of the wall and tapered side wall portions tapering inwardly to said wall, the thickness of said wall being less than the largest dimension of said beading;
- (d) said wall having a plurality of laterally extending openings longitudinally spaced along the longitudinal extent of said wall, said openings extending laterally from said adjacent base to adjacent said beading; and,
- (e) said base comprising a flange including means for mounting said wall in a standing position on a support surface.

9. The combination of claim 8 wherein said base and said wall form an off-set T in cross-section and the mounting means is included on the longer arm of the off-set T.

10. A modular wireway comprising:

- (a) base means;
- (b) said base means including fastening means for securing to a supporting structure;
- (c) a plurality of side walls arranged in spaced, parallel relation in engagement with said base means;
- (d) said base means and said side walls including integral interlocking portions to releasably retain said side walls in their spaced, parallel relation and in engagement with said base means;
- (e) said interlocking portions comprising integral flange projections on said walls and integral portions defining flange projection-receiving grooves on said base means, said grooves receiving said flange projections to interlock said side walls to said base means; and,
- (f) each flange projection receiving groove and the flange projection received therein having abutting surfaces preventing said side walls from moving laterally away from said base means whereby said base means together with said side walls as retained in their spaced, parallel relation on the base means define a wireway wherein the sidewalls are fixedly held in their spaced, parallel relation at a predetermined wireway width.

11. A wireway for retaining electrical wires in an orderly and accessible arrangement comprising:

- (a) an elongated base plate, said base plate forming the bottom of the wireway and including a pair of channel shaped retaining members longitudinally disposed one adjacent each longitudinal edge of said elongated base plate;
- (b) means to mount said base plate on a separate structure;
- (c) a pair of elongated side walls, each of said side walls including a base;

- (d) each such base having a flange portion adapted to be slidably inserted longitudinally into one of said channel shaped retaining members, said flange portion of each of said elongated side walls being removably inserted into their respective channel-shaped 5 retaining member to form a channel-like passageway for supporting electrical wires; and,
- (e) said flange portion and said channel shaped retaining members having abuttable surfaces limiting lateral movement of the side walls away from the 10 base plate thereby preventing separation of the side walls.
12. A wireway for retaining electrical wires in an orderly and accessible formation comprising:
- (a) an elongated base plate;
- (b) said base plate including side wall retaining portions longitudinally extending one on each side of said elongated base plate, each side wall retaining portion comprising a longitudinally extending back portion and a pair of longitudinally extending parallel 20 portions projecting from the longitudinal sides of said back portion, each back portion and the pair of parallel portions on each side of the back portion defining a flange receiving channel;
- (c) each pair of parallel portions including mutually 25 inwardly directed parts on the sides of each flange receiving channel;
- (d) means to mount said base plate on a separate structure;
- (e) a pair of spaced, elongated side walls, said pair of side walls including a base, said base being an off-center T in cross section with one arm of the T longer than the other, the arms of the T comprising a mounting flange which is adapted to be inserted 30 into said flange receiving channel;
- (f) said pair of spaced elongated side walls being removably carried by said base plate by inserting the mounting flange portion of the T-shaped base of each

- side rail wall into their respective flange receiving channel to form a channel-like passageway for supporting electrical wires;
- (g) said parallel portions abutting said mounting flanges of the side walls so as to limit lateral movement of the side walls relative to said base; and,
- (h) said inwardly directed parts of the parallel portions being engageable with the arms of the bases of the side walls to limit separation of the side walls from the base plate whereby the side rails with their off-set T-shaped bases may be inserted either end first into the flange receiving channel to provide a wireway of preselected fixed width.
